UNITED STATES PATENT OFFICE.

EPPA H. RYON, OF WORCESTER, MASSACHUSETTS, ASSIGNOR TO CROMPTON & KNOWLES
LOOM WORKS, A CORPORATION OF MASSACHUSETTS.

TRAVERSE-MOTION FOR WINDING YARN ON BOBBINS.

1,051,919.

Specification of Letters Patent.

Patented Feb. 4, 1913.

Application filed March 29, 1909. Serial No. 486,304.

To all whom it may concern:

Be it known that I, EPPA H. RYON, a citizen of the United States, residing at Worcester, in the county of Worcester and 5 State of Massachusetts, have invented certain new and useful Improvements in Traverse-Motions for Winding Yarn on Bobbins, of which the following is a specification.

10 My invention relates to a traverse motion for winding yarn on bobbins, and more particularly to a variable traverse motion for the yarn guide, and my invention particularly relates to improvements on the traverse 15 motion shown and described in my pending application for Letters Patent, Serial No. 427,806.

The object of my invention is to provide means whereby the direction of movement 20 of the yarn guide toward the butt of the bobbin is reversed, at a point nearest the butt of the bobbin, during the first reciprocation of said guide, and each successive reversing point is farther from the butt of 25 the bobbin, the distance between each of said reversing points and the previous one, being less and less as the butt of the bobbin is built up, and until said butt has reached 30 its full diameter, when the distance between said reversing points becomes constant during the building up of the remainder of the bobbin.

I have shown in the drawing a detached portion of a traverse motion of the type 35 shown and described in my pending application, Serial No. 427,806, above referred to, with my improvements combined therewith, sufficient to enable those skilled in the art to understand the construction and operation of the same.

Referring to the drawing:—Figure 1 is a front view of a detached portion of one 40 end of a spinning machine, with my improvements in traverse motion combined therewith, looking in the direction of arrow *a*, Fig. 2. Fig. 2 is a section, on line 2, 2, Fig. 1, looking in the direction of arrow *b*, same figure, and, Fig. 3 is a view of the ring rail or yarn guide, and connection to 50 the traverse cam.

In the accompanying drawing, 1 is a portion of the end frame of a spinning machine, 1' is the bearing or girder for the spindle rail, not shown. A traverse up and down 55 motion is communicated to a vertically re-

ciprocating ring rail or yarn guide 4, through the connector 13 to a rocker arm 11, pivotally mounted on its lower end on a stud 8 carried on a hanger 9, and a second arm 7 also pivoted on said stud 8, and carrying on an extension 7' a weight 10, and having a roll 7'' to engage a foot 6' on the vertically moving rod 6, connected with the ring rail 4, see Fig. 3, all in the usual way. The connector 13 is adjustably secured by 60 a pin 14 in an elongated slot 15' in the upper end of a cam lever 15. The hub on the lower end of said cam lever 15 is loosely mounted on a stud 16 in a stand 17 secured to the frame 1.

70 The above mentioned parts correspond with similar parts shown and described in my said application, Serial No. 427,806.

I will now describe my improvements in the mechanism for communicating a traverse 75 up and down movement to the ring rail 4, Fig. 3, or to communicate a movement to the lever 15, connected with said ring rail or yarn guide through the connector 13.

18 is a rotary shaft operated from some 80 moving part of the machine, not shown. 19 is a cam fast on said shaft, and having a cam face, in this instance on its inner end, which, in the rotary movement of said cam, engages a roll 20 on a stud 21 on a cam 85 lever 22, which has its hub 22' fast on a rock shaft 23. To the cam lever 22 is attached one end of a helically coiled contraction spring 22''. The other end of said spring 22'' is attached to the frame 1, see 90 Fig. 1. The spring 22'' acts to hold the roll 20 in engagement with the cam 19.

On the inner end of the rock shaft 23, which is suitably mounted in a bearing 24 at the lower end of a stand 25, see Fig. 2, 95 is loosely mounted a cam 26, which has two or more holes 26' therethrough. On the inner side of the cam 26 is fast a gear 27; a second gear 28 is fast on the rock shaft 23. The gear 28 has in this instance one tooth less than the gear 27. A ratchet wheel 29 is loose on the rock shaft 23, and carries a stud, on which is loosely mounted a pinion 30, see Fig. 1. The pinion 30 is of sufficient width to mesh with both of the gears 27 and 28. A washer or disk 29a extends between the ratchet wheel and the gear 28, see Fig. 2. The ratchet wheel 29 has its hub 29' provided with an annular groove or recess therein, to receive the forked end of an arm 100 105 110

31, which has its hub 31' fast on a rod 32, which is loosely and slidably mounted in a hub or boss 32' on the lower end of the stand 25, see Fig. 2. The rod 32 has in this 5 instance an engaging or ball-shaped end 32'' to be grasped by the hand of the operator to slide the rod 32, the arm 31, and the ratchet 29, thereby disengaging the teeth of the pinion 30 from the teeth of the gear 10 27, when the cam 26 may be re-set.

A helically coiled expansion and torsion spring 33 encircles the rock shaft 23, and bears against the hub 29' on the ratchet wheel 29, and has one end connected with the arm 31. The spring 33 acts to hold the ratchet wheel 29 through the washer 29^a against the gear 28, thereby causing sufficient friction between said ratchet and gear, to cause said ratchet which is loose on the 20 shaft 23 to be rocked with said gear 28, which is fast on said shaft 23, when said shaft is rocked in the direction of arrow z, Fig. 1. The outer end of the spring 33 bears against and is connected with the hub 25 34' of an arm 34; said hub 34' is loosely mounted on the rock shaft 23. The torsion spring 33 acts to yieldingly move the hub 34' and the arm 34 toward the right in Fig. 2. The hub 34' has a recessed portion at 30 34''', into which extends a pin 38' on a collar 38 secured on the rock shaft 23, in this instance by a set screw. The collar 38 acts to limit and adjust the movement of the arm 34. The arm 34 has its upper end 35 curved, or of shield-shape at 34'', see Fig. 1, which end is adapted to extend under and to engage a pin 35' which extends out from the free end of a pawl 35; the pawl 35 is suitably mounted on a stud on a stand 40 or bracket, not shown. Extending out from the shield-shaped end 34'' of the arm 34, and secured thereon, is a flattened pin or strip 34^a, which is preferably bent downwardly at its outer end and adapted to extend in the path of and to be engaged by a stud 26^a, which is loosely held in one of the holes 26' on the outer end of the cam 26, to move the arm 34 with its shield-shaped end 34'', more or less to the left in Fig. 1, and the 45 shoulder 34^b, formed by a recess 34''', away from the pin 38', when the cam 26 is re-turned to the starting position by the operator, with the roll 15^a on the cam lever 15, on the lowest part of the cam 26, as shown 50 in Fig. 1. The holes 26' on the outer end of the cam 26 are for varying the position of the stud 26^a, to cause more or less movement of the arm 34, and the shield-shaped end 34'' thereon, to the left, when the cam 60 65 26 is moved by the operator to the starting point for the beginning of the new wind. It will be understood that the farther the shield 34'' is moved toward the left in Fig. 1, at the beginning of the wind, the greater the number of teeth the ratchet 29 will be

moved by the pawl 35, until the limit of movement is reached. As the winding proceeds, the cam 26 will be rotated around the shaft 23, in the direction of the arrow z, by the ratchet and intermediate gearing, as 70 above described. The spring 33 causes the strip 34^a to remain in contact with the pin 26^a and thus follow the cam 26 around the shaft 23, until the shoulder 34^b remains in contact with the pin 38' on the collar 38, and the contact continues during the rest of 75 the wind.

It will be understood that by causing the shaft 23 to turn within the ratchet wheel 29, the same relative movement between the shaft 23 and cam 26, is caused that would be caused by turning said ratchet wheel 29 on the shaft 23, if said shaft were at rest; that is the pinion 30 is revolved about two gears 27 and 28, meshing with the teeth of both; the gear 28 being fast on the shaft 23 and having one less tooth than the gear 27, which is loose on said shaft. Said gear 27 will be caused to rotate around the shaft 23 a space equal to one of its teeth for every 85 complete revolution made by the ratchet wheel 29. 90

From the above description in connection with the drawing, the operation of my improvements will be readily understood by 95 those skilled in the art.

Through the rotation of the cam 19 and the movement of the cam lever 22, the rock shaft 23 is caused to rock, causing the gears 27 and 28, the cam 26, and the ratchet wheel 100 29, to rock also. The ratchet wheel 29 is rocked with the shaft 23 in the direction of arrow z, Fig. 1, through the frictional engagement of the gear 28 with said ratchet wheel 29. The shield-shaped end 34'' raises the pawl 35 when the shaft is rocked in the direction of arrow z, Fig. 1, and allows the ratchet wheel 29 to be rocked in the opposite direction by the cam mechanism, until the shield portion 34''' has passed from under the end of the pawl 35, and allowed the pawl to drop down and engage the teeth on the ratchet wheel 29, to hold said ratchet wheel stationary for the remainder of the movement of the rock shaft 23 in that 110 115 direction.

At the starting of the winding, the ring rail or yarn guide is in its position nearest the butt of the bobbin, and the roll 15^a on the cam lever 15 will be on the lowest part 120 of the cam 26, as shown in Fig. 1. The arm 34, having the shield shaped end 34'', is moved to the left in Fig. 1, through its engagement with the stud 26^a on the cam 26, said cam being moved by the operator in 125 the direction opposite to that indicated by arrow z, will allow the pawl 35 to drop and a greater number of teeth on the ratchet wheel 29 to pass by the end of said pawl 35, when the said ratchet wheel 29 is re- 130

volved in the direction of arrow z , and hold said ratchet through the greater part of the return movement of the rock shaft 23, at the beginning of the winding.

5 The gear 28, which is fast on the shaft 23, has in this instance one less tooth than the gear 27, and therefore the revolution of said gear 28, relative to the ratchet wheel 29, carrying the pinion 30 with it, causes 10 the gear 27 to gradually rotate the cam 26 in the direction of the arrow z , Fig. 1, whereby the cam 26 will be rocked by the shaft 23 and present a constantly changing cam surface to the roll 15^a on the cam lever 15 15, which is connected, through the rod 13, to the mechanism for communicating a traverse up and down movement to the ring rail or yarn guide 4, shown in Fig. 3. The rotation of the cam 26 causes the arm 34 20 and the shield-shaped end 34'' thereon, to gradually move to the right in Fig. 1, until the pin 38' on the collar 38 engages the notch 34''' on the hub 34'. The stud 26^a 25 may be adjusted or placed in any one of the holes 26', to vary the position of the shield 34', and cause more or less movement of said shield through the pin 34'.

It will be understood that the details of

construction of my improvements may be varied if desired.

Having thus described my invention, what I claim as new and desire to secure by Letters Patent is:—

1. In a traverse motion for winding yarn on bobbins, a rock shaft, means to communicate rocking motion to said shaft, a cam loose on said shaft, a ratchet wheel 35 yieldingly held on said shaft, a pawl, a pawl shield connected to said shaft, and connections intermediate said cam and said 40 shield, to regulate the relative movement between said ratchet wheel and said shaft.

2. In a traverse motion for winding yarn on bobbins, a rock shaft, a cam loose on said shaft, means to operate said rock shaft, 45 a ratchet wheel on said rock shaft, means to rock said ratchet wheel with said shaft in one direction, and a device to hold said ratchet wheel at rest during a portion of the return movement of said rock shaft, 50 and means to automatically regulate the engagement of said device with said ratchet.

EPPA H. RYON.
